Application September 4, 1948, Serial No. 47,788

30 Claims. (Cl. 223—37)

1

This invention relates to automatic shirt folding machines.

An object of this invention is to provide an automatic machine of the character described, comprising a table on which a buttoned up shirt to be folded is placed, with the collar down, and the back of the shirt at the top, and with the shirt sleeves extending outwardly and hanging down from the sides of the table, and including means to clamp the shirt collar to position the shirt on the table, and a swinging leaf panel hinged to the table and swingable over the top of the shirt to cover the central upper end of the shirt, and means to sequentially fold the sleeves inwardly over the top of the panel about parallel folds beyond the shoulders, fold the outer ends of the inwardly folded sleeves outwardly about parallel folds spaced close to the longitudinal middle of the shirt, fold one side of the shirt and its folded sleeve over the panel and back of the shirt, fold the other side of the shirt and its folded sleeve over the first folded side of the shirt, fold the lower or tail end of the thus far folded shirt over an adjacent portion of the shirt about a transverse fold line, and fold the folded tail end of the shirt and the portion of the shirt over which it is folded, over the panel, so that the folded shirt may then be slipped off the panel in folded condition.

Another object of this invention is to provide in a shirt folding machine of the character described, a table having a fixed table top portion formed with an opening to receive the collar of the shirt, and relatively movable blocks within said opening to engage within the shirt collar, said blocks being movable relatively toward each other to facilitate placing the shirt collar over said blocks, and being then movable relatively away from each other to engage the shirt collar and hold the same in place, a hinged panel swingable into position overlying the opening in the fixed table top portion to overlie the central upper end of a shirt on the table, a pair of parallel rods normally disposed adjacent the side edges of the table so that the shirt sleeves may overlie said rods with the outer ends of the shirt sleeves hanging down at the sides of the table, a second pair of parallel rods overlying the shirt sleeves inwardly of the first pair of parallel rods, means to move the first parallel rods to positions parallel to each other and disposed above the panel and close to one another for folding the sleeves about the second mentioned pair of parallel rods with the outer ends of the sleeves folded around the first mentioned pair of parallel rods in their inwardly moved positions

2

and extending outwardly to overlie the inwardly folded portions of the sleeves, means to grip the outwardly folded inner ends of the sleeves, and means to then move said first mentioned pair of parallel rods back from their inward positions to their outward normal positions adjacent the sides of the table.

Still another object of this invention is to provide in a shirt folding machine of the character described, a swingable side flap normally in the plane of said table, swingable about a line coextensive with the one side edge of the panel into overlying position with respect to said panel for folding one side of the shirt upon the central portion of the shirt and over the panel, and at the same time moving one of the second mentioned pair of parallel rods on the same side as said side flap to a position coextensive with an opposite side edge of said panel, and said side flap being then movable back to normal position in the plane of said table, and a second side flap normally in the plane of said table swingable about a line coextensive with said other side edge of said panel for swinging an opposite side of the shirt over the central portion of the shirt, and at the same time moving the other rod of said second mentioned pair of parallel rods to a position coextensive to the first side edge of the panel, and said second flap being then moved swingably back to a normal position in the plane of said table.

Still further objects of this invention are to provide in a machine of the character described, an end flap normally in the plane of said table, disposed between said side flaps and underlying the central lower or tail end of the shirt, and swingable about a transverse line spaced outwardly from and parallel to the outer end of the panel, for folding the lower end of the thus far folded shirt onto the central part of the thus far folded shirt, and said end flap being then swingable back to normal position in the plane of the table.

Yet another object of this invention is to provide in a machine of the character described, a middle flap normally in the plane of the table and disposed between the side flaps and between the end flaps and the swinging panel, and being swingable about a transverse line located substantially adjacent the outer end of said panel, to fold the folded central portion of the shirt over onto the top of the said panel and over the portion of the shirt folded thereabout, and said middle panel being then swingable back to normal position in the plane of the table.

Still a further object of this invention is to provide in a machine of the character described, a transverse trough below the swinging panel to receive a number of shirt bands, so that when a shirt is fully folded on the panel, the outer ends of the topmost band in the trough may be folded over the shirt and adhered together so that said panel may then be swung upwardly away from the table top, and the folded shirt then slipped off in folded condition. A cardboard or stiffening board may be placed on the first panel at its underside, so that the shirt may be folded about the cardboard as it is folded about the panel, whereby when the folded shirt is pulled off the panel, the cardboard or stiffener will come off with the folded shirt and will serve as a stiffener therefor.

Still another object of this invention is to provide in a machine of the character described, a table, a panel or leaf hinged to the table about a horizontal axis, a hand lever on the table, means connected to the hand lever for tilting the leaf downwardly so that it will drop by gravity onto the top of the table, a pair of parallel sleeves hinged to the table about a horizontal axis, said sleeves being located at opposite sides of the panel, a second hand lever, means connected to the second hand lever for swinging said sleeves from upright position to horizontal position overlying the table, a pair of shirt sleeve folding frames having portions journaled in said sleeves, portions extending at right angles to the first frame portions, and portions parallel to one another extending from said right angle portions in directions opposite to the portions within the sleeves, and means for swinging said frames about the portions journaled within the sleeves as said sleeves are swung down from upright to horizontal position, so that said parallel portions will swing outwardly as said frames are swung downwardly toward the top of the table.

Yet a further object of this invention is to provide in a machine of the character described, means to prevent swinging of the shirt sleeve folding frames downwardly, unless the swingable panel has first been tilted to drop onto the table.

Yet another object of this invention is to provide in a machine of the character described, a table including a table top, a panel hinged to the rear end of the table top and movable from upright position down to a position overlying the table top, a shirt sleeve gripper pivoted to the table about the pivotal axis to said panel, and movable from an upright position down to a position overlying the panel when the latter is dropped to the top of the table, a pair of symmetrical bell crank levers pivoted to the rear of the table below the table top and having upwardly and outwardly extending arms, parallel rods fixed to the outer ends of said arms and normally located adjacent the sides of the table top and substantially in its plane, and said bell crank having upwardly and inwardly extending arms, means engaging said upwardly and inwardly extending arms for swinging said bell crank levers about their pivot points to move said parallel rods inwardly toward each other to overlie the dropped panel at opposite sides and somewhat below the gripping member, and means controlled by the swinging of said levers for engaging the gripping member and pressing the same down against the top of the panel when the levers are swung in an opposite direction

to move the parallel rods outwardly or away from each other back to their initial positions.

Still a further object of this invention is to provide in a machine of the character described, 5 air motors controlled by solenoid operated valves, for moving said levers and the shirt folding flaps, and means to sequentially actuate the solenoids so as to operate the levers and the folding flaps in desired sequence.

10 Still another object of this invention is to provide in a machine of the character described, a table having a fixed table top portion formed with an opening to receive the collar of a shirt, a fixed block within said opening, and a movable 15 block within said opening spaced from the fixed block, lever means for moving the movable block relative to the fixed block including a portion projecting to one side of the table so that the operator may press against said part to actuate said lever means and move the movable block towards the fixed block so that the shirt collar may be easily placed over the blocks, and spring means being provided to move the movable block away from the fixed block when the operator 20 moves away from said projecting part and said lever, so that the shirt collar will be expanded by said blocks.

25 A still further object of this invention is to provide in a machine of the character described, 30 a shirt folding flap normally in the plane of the table, curved links interconnecting the table with said flaps, a lever pivoted to a fixed portion of the table, and a link connecting the lever with the flap at a point spaced from the pivotal point 35 which connects the curved link to the panel, and means for swinging the lever so that said flap will swing over the table and come down flat on top of said table, in spaced parallel relation thereto, to facilitate folding of a portion of the shirt by means of said flap.

40 A still further object of this invention is to provide a rugged and compact machine of the character described, which shall be relatively inexpensive to manufacture, which shall be sure and positive in operation, and will yet be practical and efficient to a high degree in use.

45 Other objects of this invention will in part be obvious and in part hereinafter pointed out.

The invention accordingly consists in the features of construction, combinations of elements, 50 and arrangement of parts, which will be exemplified in the construction hereinafter described, and of which the scope of invention will be indicated in the following claims.

55 In the accompanying drawings in which is shown various illustrative embodiments of this invention,

Fig. 1 is a top plan view of a machine embodying the invention, showing the panel or leaf about which the shirt is to be folded in downward position and the shirt sleeve gripper down on said leaf, and the shirt folding frames in outwardly swung positions;

Fig. 2 is a longitudinal vertical cross-sectional view taken on the line 2—2 of Fig. 1;

Fig. 3 is a cross-sectional view taken on the line 3—3 of Fig. 1;

Fig. 4 is a rear end view of the machine;

Fig. 5 is a partial elevational view of the rear end of the machine;

Fig. 6 is a cross-sectional view taken on the line 6—6 of Fig. 4;

Fig. 7 is a cross-sectional view taken on the line 7—7 of Fig. 2;

perspective views showing successive steps in the shirt folding operations of the machine;

Fig. 18 is a wiring diagram of the electrical system for controlling the operation of the machine;

Fig. 19 is a side view of one of the air cylinders;

Fig. 20 is an end view of one of the air cylinders; and

Fig. 21 is a cross-sectional view of the cam shaft illustrating the electronic motor control disc and the switches controlled thereby.

Referring now in detail to the drawings, 10 designates a machine embodying the invention. The same comprises a table structure 11, having a table top portion 12, front legs 13, and rear legs 14. The top 12 is supported by said legs and comprises a top front angle iron 15 and a rear angle iron 16 and a pair of transverse angle irons 17 and 18. It also comprises an angle iron 19 at the near side of the table and an angle iron 20 at the far side of the table.

The front legs 13 are interconnected by angle iron 21 spaced below the angle iron 15. The rear legs 14 are interconnected by angle iron 22 spaced below the angle iron 16. The legs 14 are also interconnected by an angle iron 23 spaced below the angle iron 22.

Supported by the top angle irons 15, 16, 17, 18, 19 and 20 is a top board 24. The top board 24 has a central cut-out 25 and a pair of side cut-outs 26 and 27 at opposite sides of the central cut-out. The cut-outs 26 and 27 are formed with outwardly extending notches 26a and 27a, respectively.

The top board 24 is also formed with a transverse cut-out 29 between the cut outs 25, 26, 27 and the rear end of the table. It is also formed with a substantially round cut-out 30 between the cut-out 29 and the rear end of the table.

Supported by the undersides of the angle irons 21 and 22 is a horizontal platform 32. At the rear of the table is a vertical fixed panel 33. The board 24 is formed adjacent its rear end with a central opening 35, in which is mounted a vertical bushing 36. Fixed to the underside of the board 24 is a transverse slat 37 disposed beneath the cut-out 29. Contacting the underside of the slat 37 and supporting the same is an angle iron 38. Supported on platform 32 is an angle iron 39 complementary to the angle iron 38. The angle irons 38 and 39 may be supported at their outer ends in any suitable manner.

Mounted on the slat 38 is a channel-shaped member or trough 40, open at the top and extending transversely of the table, but terminating short of the sides of the table. The channel or trough 40 is adapted to contain a stack of paper shirt bands so that the topmost band may be wrapped around a folded shirt, as will appear hereinafter, and the ends of the band adhered together to keep the shirt in folded condition.

Fixed to the underside of the table is a bracket 41 formed with a longitudinal slot 42. The bracket 41 has a portion 43 fixed to the underside of the board 24, a portion 44 parallel to and spaced below the underside of said board, and a portion 45 fixed to the angle iron 38.

Attached to the top of said portion 44 is a fixed wooden shirt collar clamping block 46 having a rear arcuate edge and a straight forward edge. The block 46 may be attached to a plate 47 to which is screwed a screw 48 passing through the slot 42. The position of the block 46 and bracket 41 may be adjusted, and the block may then be fixed in place by tightening the screw 48.

Slidably mounted on bracket 41, is a movable wooden shirt clamping block 49 fixed to a plate 50 riding on portion 44 of said bracket. Fixed to plate 50 are a pair of headed pins 51 passing through the slot 42. One of the pins 51 has a downward extension 52 and is connected by a coil tension spring 53 to portion 45 of bracket 41. Spring 53 tends to move block 49 away from block 46. The block 49 has a curved front edge and a rear straight edge. The blocks 46 and 49 are adapted to be received within the collar of a buttoned up shirt placed on the table with the front of the shirt down.

Means is provided to move the block 49 toward the fixed block 46. To this end, there is fixed to the underside of the table in any suitable manner, a vertical pivot pin 55. Pivoted to the pivot pin 55 is a lever 56 having an arm 57 formed with a bifurcated end 58 receiving the pin 52 therethrough. Arm 57 inclines rearwardly and towards the center of the table.

Extending from arm 57 at the opposite side of the pivot pin 55 is an arm 60 projecting through an opening in the near side of the table. Fixed to the arm 60 is a body contact member 61, normally inclined forwardly and away from the table, and having curved ends 61a and 61b.

When the body of the operator is pressed against member 61, lever 56 will be rotated in a counterclockwise direction, looking at Fig. 1 of the drawings, to move the block 49 towards the block 46, so as to enable the collar of the shirt to be placed over the blocks. When the body of the operator is then moved away from member 61, the spring 53 will move the block 49 away from block 46 to tightly grip the collar of the shirt.

Fixed over the front end of the board 24 is a sheet metal plate 62. Fixed over the rear end of the board 24 is a fixed plate 63 which extends from the front edge of the trough or channel 40 to the rear edge of the table. The top fixed sheet metal plate 63, however, is cut away, as at 63a, to receive the trough 40, and is also formed with a substantially circular cut-out 64 corresponding to the opening 30 in the top board 24, and into which the collar blocks 46, 49 project. It will be noted that the collar blocks 46, 49 project upwardly into the opening 30 and that the top surfaces of the blocks are in the plane of the top plate 63.

Fixed over the top board 24 is also a fixed plate 65 extending forwardly of the trough 40 and centrally disposed with respect thereto. The plate 65 is formed with a central shallow longitudinal channel 66. The plate 63 is furthermore formed with a pair of aligned slots 63b parallel to the rear edge of the table and the board 24 is formed with slots registering with said aligned slots, for the purpose appearing hereinafter.

Mounted on the board 24 is a near side flap 70, a far side flap 71, an end flap 72, and a middle flap 73. The flaps 70 and 71 are symmetrical to one another. The end flap 72 is aligned with the middle flap 73. The middle and end flaps 72 and 73 are located between the side flaps 70 and 71. The inner edges of the side flaps 70, 71 converge slightly forwardly. As will appear hereinafter, the flap 70 is pivoted so as to be swung about its inner edge through an angle of 180° to overlie the central portion of the table. The flap 71 is pivoted for movement about its inner edge through an angle of 180° likewise to overlie the central portion of the table. The end flap 72, as will appear hereinafter, is pivoted for movement about its rear end through an angle of 180° so as

to overlie the flap 73. The middle flap 73, as will appear hereinafter, is pivoted for movement through an angle of 180° about its rear end to overlie the fixed plate 65 and therebeyond.

The pivotal connection between the far side flap 71 and the table will now be described.

Attached to the underside of the flap 71 are central and side brackets 75 having horizontal flanges 76 fixed to the underside of said flap. Each of the brackets 75 has a vertical flange 77 extending down from the horizontal flange 76. Extending through the flange 77 of the brackets 75 is a bar 78 located close to flanges 76 and to the inner edges of flanges 77. The flanges 77 may be triangular in shape having upwardly and outwardly extending lower edges. Extending through a plurality of said flanges 77 is a horizontal bar 79 located in the lower corners of the flanges 77. Supported by the board 24 is a horizontal bar 80 parallel to bar 78 and disposed within the cut-out 26 and parallel to the inner edge of plate 71. The ends of the bar 80 may be supported in any suitable brackets fixed to board 24 or to any fixed part of the table. Interconnecting bars 78 and 80 are a pair of spaced, substantially U-shaped or bent links 81. The bars 78 and 80 are in the same horizontal plane, when the flap 71 is in normal position, and the links 81 project downwardly therefrom.

On platform 32 is a bracket 82 supporting a horizontal pivot pin 83. Pivoted to the pivot pin 83 is a triangular lever 84 disposed in a vertical plane. The pivot pin 83 is located adjacent the apex of the triangle. At one corner of the triangle is a pivot pin 85 and at the other corner of the triangle is a pivot pin 86. Interconnecting the pivot pin 85 with the bar 79 adjacent the central bracket 75 is a link 88 of dog-leg shape.

Means is provided to rotate the lever 84 about its pivot 83 for raising the link 88 and causing flap 71 to swing through 180° about its inner side, so as to overlie the flaps 72, 73 and the fixed plate 65 in spaced relation thereto, such action being permitted by the U-shaped links 81 which interconnect the flaps 71 with the table. To this end there is mounted at the near side of the table, a pivot 89. Pivoted thereto is an air motor 90 controlled by solenoid operated valves, well known in the art, such as model BSM-1 manufactured by The Bellows Company of Akron, Ohio.

The motor 90 comprises a cylinder 91 and a piston 92 slidable therein and pivoted to the pivot pin 86. When the piston 92 is moved to the right, looking at Fig. 3, lever 84 will be rotated in clockwise direction about the pivot pin 83 for pulling down the link 88 and moving the flap 71 back to horizontal position. When the piston 92 is moved to the left, looking at Fig. 3, the lever 84 will be turned in a counterclockwise direction raising the link 88 and swinging the flap 71 over through an angle of 180°.

The valves which cause the piston to move to the left or to the right are controlled by retract and advance solenoids 94 and 95, grounded as at 96, and connected to terminal posts 97 and 98, respectively. The electrical connections for operating the solenoids in proper sequence will be described hereinafter.

It will be noted that when the lever 84 is swung in a counterclockwise direction, and the link 88 is lifted, the flap 71 is subjected to pivotal movement in a counterclockwise direction about the pivot bar 78 relative to the links 81, and the links 81 are also subjected to pivotal movement in a

counterclockwise direction about the pivot bar 89. Such action permits the flap 71 to move up, then around, through an angle of 180° and then down flat over the table. Such movement of the flap 71 has been found to be extremely advantageous for the shirt folding operation to be described hereinafter.

The links 81 are interconnected by a stop pin 81a adapted to contact wall 78 to limit relative movement between the links 81 and flap 71. When the link 88 begins to rise, the links 81 will first begin to rotate about the pivot 89 and thereafter the flap 71 will begin to rotate about the pivot 78. The bent links extend around the edges of flaps 72, 73 and table plate 65. The upper end of link 88 inclines upwardly and toward the center of the table to project above and inwardly of the adjacent edge of flap 73.

The near side of flap 70 is symmetrical to the far side flap 71 and is similarly mounted for symmetrical pivotal movement through an angle of 180°, likewise by means of brackets 75a fixed to the underside of the flap and carrying a rod 79a connected by link 88a to a lever 84 pivoted on a bracket 82, mounted on platform 32 and connected to the opposite side of the table by a solenoid operated valve air motor 91a. In other words, the pivotal arrangement for the flap 70 is similar to and symmetrically disposed with respect to the pivotal connections for the flap 71.

The air motor 91a is the same as air motor 81 and likewise comprises solenoids 93 and 95 grounded together as at 96 and connected to terminal posts 97 and 98. As will be seen herein-after by reason of sequential energization and deenergization of the solenoids of air motors 91 and 91a, the near flap 70 will first be caused to rotate from normal position through an angle of 180° and then back to normal position automatically, and thereafter the far side flap 71 will be caused to rotate through an angle of 180° from normal position and then back to normal position.

The pivotal means for the end flap 72 will now be described.

Fixed to the underside of the rear end of end flap 72 is a pair of angular brackets 100 having horizontal flanges 101 fixed to the underside of the flap 72 and triangular shaped vertical flanges 102 at right angles to said flanges 101. Carried by the flanges 102 adjacent their upper rear corners is a horizontal transverse bar 103. Interconnecting the lower corners of the flanges 102 is a horizontal transverse bar 104. Fixed to the top board 24 of the table is a horizontal bar 105 parallel to bar 103. The bars 103 and 105 are interconnected by a pair of links 106 similar to the U-shaped links 81.

The links 106 carry a stop bar 107 adapted to contact the brackets 100 to limit relative movement between the links and the end flap 72. Mounted on the platform 32 is a bracket 108 carrying a pivot pin 109. Pivoted to the pivot pin 109 is a triangular lever 110. The lever 110 carries the pivot pin 111 at one corner interconnected by a dog-leg shaped link 112 to the pivot bar 104. Carried by the lever 110 is a pivot pin 115. Fixed to the underside of the platform 32, in any suitable manner, is an air motor 91b similar to the air motors 91 and 91a.

It carries a piston rod 113 connected by link 114 to the pivot pin 115. As the piston rod 113 is moved to the right, lever 110 will be rotated about pivot 101 in a counterclockwise direction 75 raising the link 112 and causing flap 72 to rotate

through an angle of 180° over the top of the middle flap 73. Here, likewise, links 106 will rotate about pivot 105 in a counterclockwise direction and the end flap 72 will rotate in counterclockwise direction about the pivot 103 so that the flap may move up over and then down above the top of flap 73 and spaced in parallel relation thereto. When the piston rod 113 is moved to the left, the lever is rotated in a clockwise direction and the flap 72 is moved back to normal position. The air motor 91b is likewise controlled by retract and advance solenoids 94, 95 grounded together as at 96, and connected to terminal posts 97, 98, respectively. The electrical wiring diagram and electrical control for the solenoids will be described hereinafter.

Attached to the underside of the middle flap 73 are brackets 100a similar to brackets 100 and carrying pivot rods 103a and 104a similar to the rods 103 and 104. The rods 103a are connected by links 106a similar to links 106, to the pivot rod 105a carried by the top board 24. The links 106a also carry a stop rod 107a similar to the stop rod 107.

On platform 32 is a bracket 108a to which is pivoted a triangular shaped lever 110a as at pivot pin 109a. Lever 110a carries a pivot 111a connected by dog-leg shaped link 112a to the pivot pin 104a. Fixed to the underside of the platform 32 is an air motor 91c similar to the air motors 91, 91a, 91b, and including a piston rod 113a connected by link 114a to a pivot pin 115a on the triangular lever 110a. Here, likewise, when the piston rod 113a is moved to the right, flap 73 will be rotated about its forward end through an angle of 180°, first moved up, then around, and then down in spaced relation to the top of the table. When the piston rod 113a is moved to the left, the flap 73 is swung back to normal position in the plane of the table.

Attached to the rear plate 33 is a pair of bearing members 128 projecting above said plate and having aligned bearing openings in which is rotatably mounted a horizontal shaft 121 disposed substantially at the level of board 24 and parallel to its rear edge. The shaft 121 extends to the near side of the machine and is formed with a downwardly curved portion 122 from which extends upwardly a handle 123 provided with a hand knob 124.

It will now be understood that when the knob 124 is grasped and the handle 123 is turned, the shaft 121 would be rotated about its axis. Mounted for free rotation about the central portion of the shaft 121 is a leaf or panel 125 about which the shirt on the table is to be folded. Said leaf or panel 125 has a pair of parallel rearwardly extending tongues or projections 126 to the undersides of which are attached plates 127 formed with aligned apertured ears 128 through which the shaft 121 extends. The portions 126 of the leaf extend rearwardly beyond the shaft 121 and hence beyond the table. The leaf 125 may swing from vertical position, in which position the tongues 126 and their supporting plates 127 will contact the rear plate 33, down to horizontal position, as shown in the drawings, overlying the central portion of plate 63 crossing the trough 40 and overlying plate 65. Thus, the forward portion of the leaf 125 is disposed between the side flaps 70 and 71 and the front edge 125a of the leaf is adjacent the rear end of the middle flap 73. The central portion of said rear edge may be notched out as at 125a.

It will be noted that there is a space or cut- 75 towards the sides of the table. Extending from

out between the tongue portions 126 of the leaf 125, for the purpose hereinafter appearing.

Means is provided for tilting the leaf 125 to start rotation thereof from vertical down to horizontal position, so that it moves sufficiently from vertical position to drop by gravity fully to horizontal position. To this end there is mounted in suitable bearings 130 and 131 on the table, a horizontal shaft 132 disposed below the table top and forwardly of plate 33. The shaft 132 extends beyond the near side of the table, and fixed thereto is a sleeve 133 from which extends a handle 134. The shaft 132 is rotated upon swinging the handle 134. Plate 33 and the angle iron 16 are formed with registering openings 135 below one of the tongues 126 of the leaf 125. Fixed to the shaft 132 is an angle shaped arm 136 having a rearwardly projecting horizontal finger 137 projecting through the registered openings 135. When the shaft 132 is swung in a counterclockwise direction, looking at Fig. 6 of the drawings, the finger 137 will engage one of the tongues of the leaf, should the leaf be in vertical position, thereby rotating the leaf in a clockwise direction until the leaf drops by gravity into horizontal position overlying the top of the table.

Means is provided to prevent rotation of the shaft 121 by means of the handle 123 in clockwise direction, looking at Fig. 5, until the handle 134 is swung in a counterclockwise direction, looking at Fig. 5, to cause the leaf to drop to the table. To this end, there is fixed to the sleeve 133 a radial finger 138 engaging the curved portion or bend 122 in the shaft 121. It will be noted that the handle 123 cannot be turned in a clockwise direction because the finger 138 will stop it. However, should handle 134 be swung in counterclockwise direction, finger 138 moves away from the bend 122, and the shaft 123 can then be rotated in a clockwise direction, for the purpose hereinafter appearing.

Fixed to the shaft 121 and located at opposite sides of the leaf 125 are parallel aligned sleeves 140 disposed at right angles to said shaft. Sleeves 140 have aligned openings through which the shaft 121 passes. Shaft 121 may be fixed to the sleeves 140 by means of set screws or in any other suitable manner. When the shaft 121 is rotated, the sleeves 140 will rotate therewith. The sleeves 140 have through openings 141 extending at right angles to the longitudinal through openings 142 through which the shaft 121 passes. The sleeves 140 may likewise move from upright to horizontal position independently of the leaf 125.

Rotatably mounted in the sleeves 140 are a pair of similar symmetrical shirt sleeve folding frames 143. Each of the frames 143 comprises a portion 144 journaled in the sleeve 140. The frames 143 will be described in their horizontal positions overlying the table. When the frames are in such position, there extends from the rear end of each portion 144 an inwardly and somewhat downwardly inclined finger 145.

On portion 144 are collars 146 to prevent sliding movement of said portion within the sleeve 140. Extending at right angles to the forward end of each of said portions 144, is a portion 147 overlying the table and formed with a downwardly bent intermediate portion 148, projecting into notch 63b in the table top 63 and into the opening in the board 24 therebelow. The purpose of the intermediate bent portion 148 will be apparent hereinafter.

It will be noted that said portions 147 extend towards the sides of the table. Extending from

said portions 147 are bar or rod portions 150 which are parallel to each other and parallel to the sleeves 140. The portions 150 project forwardly and their outer ends overlap the side flaps 70 and 71. The frame portions 150 are disposed inwardly of the side edges of the table, as shown in Fig. 1 of the drawing.

It will be noted that when the side flap 70 is rotated from normal position to a position overlying the central portion of the table, the outer end of portion 150 of the frame 143 adjacent thereto, will be engaged by said flap and said frame will be rotated about its sleeve 140 through an angle of 180° bringing the frame portion 150 to a position parallel to and adjacent the longitudinal edge 125c of the leaf 125, closer to the far side of the table. When the flap 70 rotates back to normal position, the frame which was rotated thereby will remain in the position to which it was moved.

Likewise, when the flap 71 at the far side of the table is rotated through an angle of 180°, the forward end of portion 150 of the frame 143 adjacent thereto, will be engaged thereby, and said frame will be rotated through an angle of 180° bringing said portion 150 adjacent to and parallel with the edge 125d of the leaf 125, which is closer to the near side of the table. When the flap 71 is moved back to normal position, frame 143 moved thereby will remain in its moved position. With the frames 143 both turned inwardly from the position shown in Fig. 1, said frames together with the leaf and a shirt folded thereabout, as will be hereinafter described, may be moved upwardly to vertical position, as shown in Fig. 17, and in such position, the shirt may be pulled off the leaf. Should the leaf 125 thereafter be dropped, and the handle 123 then rotated in a clockwise direction from the position shown in Fig. 5, the sleeves 140 will be rotated in clockwise direction, swinging the frames 143 from upright to horizontal position.

Means is provided automatically swinging said frames 143 from their inwardly turned positions to their outwardly turned positions, as shown in Fig. 1, as said frames move from vertical to horizontal positions. To this end, plate 33 is formed with a pair of through slots 151, symmetrically disposed on opposite sides of the middle of said plate. The slots 151 are located inwardly of the sleeves 140 and therebelow. Pivoted to said shaft 132 are a pair of levers 152 having forwardly extending arms 152a connected by coil tension springs 153 to anchors 153a fixed to the angle iron 22. The springs 153 tend to rotate the levers 152 in a clockwise direction. The movement of the levers is limited by the upper edges of the slots 151. On the rearwardly extending arms 152b of the levers 152 are downwardly, outwardly and rearwardly, and then rearwardly and upwardly curved cams 154 terminating in upwardly projecting straight fingers 155.

It will be noted that the curved portion 154 at the far side of the table is bent upwardly more sharply than the curved portion 154 at the near side of the table. The purpose for such construction will appear hereinafter. In other words, the straight finger portion 155 at the near side of the table is shorter than the straight finger portion 155 at the far side of the table. It will be noted that the bends in the fingers 155 are located below and in the planes of the portions 144 of the frame members 143. When the frames 143 are swung inwardly, and the portion 144 of said frames are in upright or vertical position,

the tails or fingers 145 will project outwardly towards the sides of the table and somewhat rearwardly.

Should the shaft 121 then be turned to swing the frames 143 to horizontal position, the tails 145 will be engaged by inner edges of the curved portions 154 and as the frames 143 move down to the table, contact of the tails 145 with curved portions 154 and the fingers 155 will swing the frames 143 outwardly towards the sides of the table.

The finger 155, closer to the far side of the table is longer than the other finger 155, so that the frame 143 closer to the far side of the table will be first swung outwardly and then the frame 143, closer to the near side of the table, will be thereafter swung outwardly.

As will appear hereinafter, the flap 70 is swung back and forth before the flap 71, and therefore

20 a portion of the frame 143 at the near side of the table will lie beneath a portion of the frame 143 at the far side of the table, so that the frame 143 at the far side of the table being on top, must be swung outwardly somewhat in advance of the 25 outwardly swinging movement of the other frame 143, and that is accomplished by the fact that the shape of the cam 154, closer to the far side of the table is such that the frame 143 closer to the far side of the table will start turning before the other frame.

As the arms swing outwardly, the arms 162 will be depressed against the tension of the springs 153 and after the tails 145 have moved away from said fingers 155, the springs 153 will again raise said arms.

Fixed to the rear plate 33 adjacent the lower edge thereof, are a pair of parallel, horizontal, longitudinally, rearwardly extending pivot pins 160. Pivoted on said pivot pins 160 are a pair of similar, 40 symmetrically disposed bell crank levers 161. Each bell crank lever 161 has an upwardly and outwardly inclined arm 162, and an upwardly and inwardly inclined arm 163.

45 Fixed to the outer ends of the arms 162 are sleeves 163. Fixed within the sleeves 163 are the rear ends 164 of bars 165. Between the rear ends 164 and the main portion of the arms 165 are inwardly bent portions 166. Fixed to the sides of the table and extending therebeyond, are transversely curved channels or troughs 168 into which the arms 165 project. It will be noted that the arms 165 are parallel to each other and are normally disposed closely adjacent the sides of the table. The upper ends of the arms 163 are formed 50 with longitudinal slots 169. Fixed to the angle iron 23 of the table support is a bracket 170. Supported by the bracket 170 is the cylinder of a vertical air motor 91d, similar to the air motors 91, 91a, 91b, 91c.

55 Slidable in said air motor is a piston having a piston rod 171 projecting upwardly. Fixed to the upper end of the piston rod 171 is a block 173 formed with a central opening to receive the upper end of the piston rod. The block 173 may be fixed to the piston rod in any suitable manner. It is formed with outwardly extending slots 174 into which the upper ends of the lever arms 163 project. Fixed to said block and traversing the slots 174 are transverse pins 175 passing through the slots 169.

60 It will now be understood that when the piston rod 171 moves downwardly, the levers 161 are rotated in opposite direction to swing the rods 165 from the position shown in Figs. 1 and 8 65 to a position shown in Fig. 10, overlying the leaf

125. When the rods 165 overlie the leaf 125, they will be spaced closely to one another in parallel relation, for the purpose hereinafter appearing.

When the piston rod 171 thereafter moves upwardly the levers 161 are swung outwardly to bring the rods 165 back to normal position. As will appear hereinafter, when the levers 161 are moved from the position shown in Fig. 9 to the position shown in Fig. 10, they will fold the sleeves of a shirt about rod portions 150 of the frames 143 inwardly with the outer ends of the sleeves folded about said rods 165 and extending outwardly.

Means is provided to clinch such inwardly folded sleeves to retain the same in the position of Fig. 10 when the levers are thereafter swung outwardly and bars 165 move away from each other. To this end, there is pivoted to the central portion of the shaft 121, an ear 180 located between the rear tongues 126 of the leaf 125 and apertured to receive said shaft. Supported by the ear 180 is a lock bar 181 movable from upright to a horizontal position overlying the central portion of the leaf 125. The lock bar 181 is formed at its outer end with a pair of spaced parallel arms 152. It is also formed with an intermediate through slot 184, and is provided with a transverse fixed pin 185 crossing the slot. Slidably mounted in the bushing 36 which is fixed to the table top, is a rod 186 formed with a hook 187 at its upper end adapted to move through the opening or slot 184 and engage the pin 185.

The platform 32 is formed with a through opening 190 disposed below the rod 186. Fixed to the lower end of the rod 186 is a long pin 191 projecting downwardly through the opening 190. Fixed on the pin 191 is a collar 192 disposed above the platform 32 and surrounding said pin is a loose washer 193 disposed below said platform. Also fixed to the pin 191 above its lower end is a collar 194. Interposed between the collar 194 and the washer 193 and surrounding the pin 191, is a coil compression spring 195. Pivoted to a fixed pin 196 at the rear end of the frame, is a lever 197 having a forwardly extending arm 198 engaging the underside of the collar 194. Arm 198 may have an opening through which the lower end of pin 191 projects. The lever 197 has a rearwardly extending arm 199.

Fixed to the block 173 is a plate 200 projecting towards the wall 33. On said plate 200 is an adjustable screw 201 located directly above the arm 199 of the lever 197. When the piston rod 171 descends to swing the bars 165 inwardly, the hook 187 is disengaged with respect to the lock member 181. In fact, the transverse pin 185 will contact the top of the hook when member 181 is swung downwardly. When the bars 165 are swung inwardly toward each other, they will move beneath the arms 182 of member 181. This action occurs when the piston rod descends.

At the lower end of the stroke, however, screw 201 will contact the arm 199 of the lever 197 and rotate said lever in a counterclockwise direction raising the rod 186 to permit the pin 185 to drop below the hook 187. As the member 171 begins to move up for moving the bars 165 away from each other, screw 201 will release the lever 197, and the spring 195 will then cause the hook 187 to press down against the pin 185 for resiliently pressing member 181 downwardly, so that the arms 182 will clinch the sleeves which were folded beneath said arms by the rods 165.

Thus, although the rods move away from each other, from the position shown in Fig. 10 to the position shown in Fig. 11, the sleeves will remain in inwardly clinched condition.

Means is provided for controlling the energization of the advance and retract solenoids 94 and 95 of the air motors 91, 91a, 91b, 91c, 91d, sequentially and automatically, the arrangement being such that the air motor 91d is first actuated to retract and then advance the piston rod and its piston; the air motor 91a controlling the flap 70 at the near side of the table is then actuated to first retract and then advance its piston; the air motor 91 controlling the flap 71 at the far side of the table is thereafter actuated to first retract and then advance its piston; the air motor 91b controlling flap 71 is then actuated to first advance and then retract its piston; and the air motor 91c controlling flap 73 is thereafter actuated to first advance and then retract its piston.

To this end, there is fixed to the underside of the platform 32, an angle iron 210. Supported by the front legs 13 is a pair of parallel insulating strips 211 and 212. Attached to the angle iron 210 and extending downwardly therefrom is a plate 214 disposed in a vertical plane. The strips 211 and 212 are fixed to the plate 214 by a pair of longitudinal members 215 and 216. Supported at the ends of the plate 214 are a pair of parallel plates 217 disposed in vertical planes.

Journalled in the plates 217 is a horizontal cam shaft 218, carrying ten similar insulating circular discs 219 each formed with a notch 220. The discs 219 are fixed to rotate with the shaft 218. The notches 220 of the discs 219 are successively spaced angularly, one with respect to the other. The spacing may be of equal angles so that each notch is spaced 36° from the notch of the successive disc.

Also on shaft 218 is fixed a disc 221 of smaller diameter than the disc 219 and provided with a projecting lug 222. In normal position, when the machine is not operating, the first disc 219 is positioned with its notch 220 in horizontal position, and the disc 221 also has its lug in horizontal position in alignment with the notch 220 of the first disc 219.

Attached to the upper strip 211 is a downwardly projecting spring switch element 224 aligned with the disc 221. Attached to the lower strip 212 and projecting upwardly therefrom is spring switch element 225 adapted to contact the switch element 224. On switch element 225 is a roller 226. When the disc 221 is in initial position, shown in Fig. 19, the lug 222 on disc 221 presses back against the roller 226 and moves switch 225 out of contact with respect to switch 224, so that the switch 224, 225 is normally open.

Attached to the strip 211 are ten downwardly extending switch elements 227 aligned with the ten discs 219, respectively. Attached to the bottom strip 212 are ten upwardly extending switch elements 228 adapted to coat with the respective switch elements 227. On each switch element 228 is a roller 229 adapted to contact one of the discs 219. When the roller 229 is in the notch 220 of any one disc, the switch which carries said roller will contact its respective switch 227, and when the disc 219 rotates the roller 229 will be pressed back and the switch will open.

In the wiring diagram, for the purpose of clarity, the ten successive switches controlled by the discs 219 will be designated by the numerals

1a, 1b, 2a, 2b, 3a, 3b, 4a, 4b, 5a, 5b, respectively.

The first switch 1a is normally closed. Switches 1b, 2a, 2b, 3a, 3b, 4a, 4b, 5a, 5b are normally open.

The shaft 218 is connected in any suitable manner for rotation by an electric motor 230 mounted in any suitable manner on the plate 214. Said shaft 218 may be geared to the armature of the motor 239 in the usual manner. The motor 230 may be a 110 volt motor with a pair of field windings 231 and 232. The windings 231, 232 are connected together in parallel. One side of said windings is connected by wire 233 to one lead 233a of a suitable power supply, for example, 110 volts 60 cycle. The other side of said field windings 231, 232 is connected by wire 234 to said switch element 225, and also by wire 235 to one arm 236 of a double pole, single throw, normally open, table switch 237. The other arm 238 of said switch is connected by wire 239 to a fixed contact 240 forming part of a single pole, single throw, safety manual switch 241. Said switch 241 comprises a switch arm 242 adapted to engage the contact 240. Said switch arm 242 is connected by wire 243 to the coil 244 of a step down transformer 245 adapted to reduce the voltage. It may transform 110 volts down to 8 volts. The coil 244 is grounded as at 246. The other coil 247 of the transformer 245 is connected by wire 248 to the lead 233a, and by wire 249 to wire 250 connected through a single pole, single throw switch 250a to the other lead 251 of the power supply.

The second arm 238 of the switch 237 is connected by wire 252 to the switch elements 227 of switches 1b, 2a, 2b, 3a, 3b, 4a, 4b, 5a, 5b, which are in parallel. The arms 236 and 238 of the table switch 237 are adapted when closed to engage a pair of spaced contacts 253 and 254. The contact 253 is connected by wire 255 to the switch element 227 of switch 1a. The fixed contact 254 is connected by wire 256 to wire 250 and to switch element 224.

Switch elements 228 of switches 1a, 2a and 3a are connected by wires 257 to the binding posts 97 of the retract solenoids 94 of the air notches 91d, 91a and 91. Switch elements 228 of the switches 1b, 2b and 3b are connected by wires 258 to the binding posts 98 of the advance solenoids 95 of the air motors 91d, 91a and 91. The switch elements 228 of the switches 4a and 5a are connected by wires 259 to the binding posts 98 of the advance solenoids 95 of the air motors 91b and 91c. The switch elements 228 of the switches 4b and 5b are connected by wires 260 to the binding posts 97 of the retract solenoids 94 of the air motors 91b and 91c.

The switch 237 is located below the downwardly bent portion 148 of the frame member 143 at the near side of the table, so that when said frame member is swung down to the table, said bend will close the switch and start the cycle of operation of the air motors, as will be described hereinafter. The bend 148 of the frame members 143 are so located as to straddle the lock member 181. Furthermore, the bar 165 at the near side of the table passes above and through the bend 122 of the shaft 121 so as not to interfere with said shaft.

Attached to the underside of the forward part of plate 121 is a pair of leaf springs 270 projecting forwardly therefrom. A cardboard or stiffener about which a shirt is to be wrapped, may be inserted between springs 270 and the underside of the leaf or panel 125, one edge of the cardboard contacting the forward edges 127a of

the plates 127. The cardboard is designated by the numeral 271.

It will be noted that the tail flap 72 and the middle flap 73 are formed with central longitudinal shallow grooves 72a and 73a in alignment with each other. Furthermore, the plate 65 is formed with a central shallow groove 65a aligned with the grooves 72a, 73a. Said grooves 65a, 73a and 72a are for the purpose of receiving the buttons of the shirt placed on the table for folding.

The operation of the machine will now be described. The machine at the start of the operation is in the position shown in Fig. 8, with the leaf 125 up, with the frames 143 swung inwardly over the rear of the leaf, and with the lock bar 181 likewise upright against the upper side of the leaf. Also in the initial position of the machine, bars 165 are swung outwardly.

The switches 250a and 241 are first closed. At this time, as stated before, only switch 1a is closed but switch 224, 225 and the switches 1b, 2a, 2b, 3a, 3b, 4a, 4b, 5a, 5b are open.

The closing of the switches 250a and 241 will not energize the motor because switch 224, 225 is normally open. Also the solenoids of the air motors are not energized because switches 1b, 2a, 2b, 3a, 3b, 4a, 4b, 5a, 5b connected to said switch 241 are normally open and switch 1a is connected to the fixed contact 253 which has not yet been bridged by the arm 238 of the switch 237.

The shirt S is placed on the table with the front of the shirt down. The shirt is preferably buttoned and the middle of the shirt is aligned with the grooves 65a, 73a and 72a. The collar of the shirt is inserted now into the opening 64 of the table top and the blocks 46, 49 are received within the collar. Before inserting the collar, the operator presses against member 61 to bring the blocks 49, 46 together. After the collar has been properly positioned, the operator moves away from member 61 and the block 49 is moved away from block 46 to grip the collar. The shirt sleeves SS extend outwardly over the bars 165 and around the trough or channels 166 and hang down at the sides of the table. The operator then turns the handle 134 in a counterclockwise direction, looking at Fig. 5, tilting the leaf 125 and causing it to drop onto the table and over the upper central portion of the back of the shirt. At the same time, the lock bar 181 swings down loosely over the top of the leaf but is held in somewhat raised position by reason of contact with the top of the hook 187 with the underside of the pin 185. The operator then swings the handle 123 in a clockwise direction, looking at Fig. 5, causing the sleeves 149 to swing down to horizontal position. At the same time the frames 143 swing outwardly and downwardly due to engagement of the tails 145 with the curved loop cams 154, 155.

When the frames 143 are swung downwardly and outwardly, they will be in the position shown in Fig. 9 with the bars 150 overlying the sleeves SS inwardly of the bars 165. When said frames come down the bend 148 of the frame 143 will close the switch 237 thereby interconnecting wire 235 with fixed contact 254 and interconnecting wires 252 and 239 with the fixed contact 253.

The field coils 231, 232 for the motor 236 will now be energized through lead 233a, wire 233, coils 231, 232, wire 234, wire 235, wire 256, wire 250, switch 250a, and lead 251. At the same time 8 volt current will pass through switch 1a, which is normally closed, to the retract solenoid 94 of

the air motor 91d. As soon as the motor starts turning, switch 224, 225 will close as the lug 222 will move away from roller 226 thereby keeping the motor energized even after switch 237 opens, as will appear hereinafter.

When the cam shaft 213 has made a complete revolution, switch 224, 225 again opens and by that time, the switch 237 also is open, whereby to shut off the motor. Thus, the cam shaft makes one revolution for each operation. The closing of switch 237 as stated before, permits energization of the retract solenoid 94 of the air motor 91d at the rear end of the table causing the piston rod 171 to move downwardly and rotate the bell crank levers 161 inwardly, bringing the rods 165 inwardly, and beneath the arms 182 of the locking lever 181. The sleeves 280 thereby become folded over and inwardly, as at 280, about the rods 150, and also are folded over the rods 165, as at 281, and the outer ends 282 of the sleeves then extend outwardly.

At the lower end of the stroke of the piston rod 171, hook 186 is raised to overlie the pin 185 and as the cam shaft continues to rotate, switch 1b will close and switch 1a opens to deenergize the retract solenoid of the air motor 91d, and also to energize the advance solenoid 95 of air motor 91d to advance or raise the piston rod 171 thereby causing the hook 187 to engage pin 185 and press down on the locking member 181 and at the same time the levers 161 are swung outwardly to swing the rods 165 away from each other. The inner folds 281 of the shirt sleeves are however gripped or clinched by the arm 182 of the locking member 181. This movement is illustrated in Fig. 11 of the drawing.

As the cam shaft continues to rotate, switch 2a is closed and switch 1b opens, again causing the advance solenoid of air motor 91b to deenergize and also causing the retract solenoid 94 of the air motor 91a to become energized for retracting its piston and causing the flap 70 to turn 180° to the position shown in Fig. 12. When this is done, the side of the shirt at the near side of the table, together with the folded sleeve at said side, is folded over the central portion of the back of the shirt. At the same time frame 143 at the near side of the table is swung 180° about its sleeve 140 to the position shown in Fig. 12 thereby opening the switch 237. By this time switch 224, 225 is closed and switch 1a has been opened, so that the operation of the machine is not affected. As the cam shaft continues to rotate, switch 2b is closed and switch 2a opens thereby deenergizing the retract solenoid of the air motor 91a and energizing the advance solenoid of said air motor, thereby causing the flap 70 to move back to normal position on the table top, but leaving the frame 143 which was swung over by said flap in its swung over position.

As the cam shaft continues to rotate, switch 3a closes and switch 2b opens, thereby deenergizing the advance solenoid of air motor 91a and energizing the retract solenoid of the air motor 91, thereby causing the side flap 71 at the far side of the table to swing over 180° and fold the side of the shirt at the far side of the table over onto the part of the shirt which was folded over the central portion of the shirt by the flap 70. At the same time, the frame 143 at the far side of the table is swung over the first frame.

As the cam shaft continues to rotate, switch 3a opens again and switch 3b closes, thereby deenergizing the retract solenoid of the air motor 91 and energizing the advance solenoid of said air motor, and thereby causing the flap 71 to swing

back to its normal position leaving the portion of the shirt which is folded, in folded condition. The swinging of the flap 71 away from normal position is illustrated in Fig. 13 of the drawing.

5 The position of the shirt when the flap 71 at the far side of the table swings back to normal position, is illustrated in Fig. 14 of the drawing.

As the cam shaft continues to rotate, switch 3b opens thereby deenergizing the advance solenoid of the air motor 91 and energizing the advance solenoid of the air motor 91b causing the end flap 72 to swing over 180° and fold the tail end of the shirt over onto the middle part of the shirt, as illustrated in Fig. 15 of the drawing.

As the cam shaft advances, switch 4a opens and switch 4b closes thereby deenergizing the advance solenoid of air motor 91b and closing the retract solenoid of said air motor, thereby causing said end flap 72 to swing back to normal position, leaving the tail end of the shirt in folded condition.

As the cam continues to rotate further, switch 4b opens and switch 5a closes, thereby deenergizing the retract solenoid of air motor 91b and energizing the advance solenoid of the air motor 91c and causing the middle flap 73 to swing over 180° to a position shown in Fig. 16 and folding the folded tail of the shirt onto the upper part of the shirt and leaf 125. As the cam shaft further advances, the switch 5a is open and the switch 5b is closed, thereby deenergizing the advance solenoid of the air motor 91c and energizing the retract motor of said air motor, causing the middle flap 73 to swing back to normal position, leaving the shirt completely folded around the leaf 125 and around the bars 150 and also around the cardboard which was mounted on the leaf.

40 As the cam shaft continues to rotate back to its original position completing 360° rotation, switch 224, 225 opens, and switch 1a closes. The opening of switch 224, 225 deenergizes the motor and the cam shaft will stop rotating because the switch 237 had been opened when the frame 143 at the near side of the table was swung over by the flap 70.

The operator then folds one of the paper bands within the channel 140 around the folded shirt and glues the ends of the band together in a well known manner. The operator then swings the handle 123 in a counterclockwise direction lifting the sleeves 148 and the frames 143, but since the shirt is wound both on the leaf and the bars 150 of the frame 143, the leaf will also be lifted, and the folded shirt together with the cardboard may then be easily slipped off the leaf.

50 The handle 124 is swung in a clockwise direction to move the finger 137 out of the way so that the leaf may be raised. The machine is now back to normal position and the operation of the machine will start all over again.

As the locking member 181 comes up, it will pull up on the rod 166 and become disengaged from the hook 187.

55 If desired, the legs at the far side of the table may be raised so that the table will slant upwardly from the near side of the table to the far side of the table. Such an arrangement will 70 make it easier for the operator to manipulate the shirt when positioning the same on the table.

It will be noted that the table pole, single throw contacts switch 237, is located on the table top 12 directly under one of the arms 147 as indicated by numeral 284 in Fig. 1.

It will be further noted that said switch 237 will close when arms 147 are rotated from a vertical to a horizontal position. The closing of switch 237 will start motor 230 through leg 236 of said switch. The other leg 238 of said switch will energize the retracting solenoid on air motor 91a. Switch 237 remains closed until the side flap 79 has been operated. The operation sequence timing motor 230 continues to operate through the switch 224 and 225 until the cycle has been completed.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described our invention, we claim as new and desire to protect by Letters Patent of the United States:

1. A shirt folding machine comprising a table formed with an opening to receive a shirt collar, a pair of relatively movable members within said opening to grip said shirt collar, manual means to move one of said members toward the other, spring means to move said one member away from said other, a leaf hinged to said table and adapted to drop onto the table to overlie said opening, a locking member hinged to the table and overlying said leaf, and means to lock said locking member against the leaf when the leaf is in horizontal position.

2. A shirt folding machine comprising a table on which a shirt to be folded may be placed, a leaf hinged to the table and adapted to move from upright position down to a position overlying the shirt on the table, a locking member pivoted to the table and adapted to swing from upright position down to a position overlying the leaf when the latter lies on the table, a pair of bars parallel to and spaced from the side edges of the leaf adapted to engage beneath the sleeves of the shirt on the table, means to move said bars inwardly from normal position toward each other and between said locking member and said leaf, to fold portions of the sleeves of the shirt over said leaf, and to bring portions of the sleeves between the leaf and the locking member, means for locking the locking member to the leaf to grip the portions of the sleeves which are between the locking member and the leaf, and means to thereafter move said parallel bars away from each other back to normal position thereby leaving the gripped portions in gripped condition.

3. A shirt folding machine comprising a table on which a shirt to be folded may be placed, with the front of the shirt down, means on the table to grip the collar of the shirt on the table, a leaf pivoted to the table and adapted to move from upright position down to the top of the table to overlie the central portion of the back of the shirt, a pair of parallel bars at the top of the table in spaced parallel relationship to the side edges of the leaf, and the sleeves of the shirt extending outwardly and over said bars and hanging down from the sides of the table, a second pair of parallel bars overlying said sleeves and spaced inwardly from the first pair of parallel bars, a locking member pivoted to the table and movable

from upright position down to a position overlying the leaf when the latter is lying on the table, means to move the first pair of parallel bars inwardly toward each other to a position beneath the locking member for folding the sleeves around the second mentioned parallel bars and to bring portions of the sleeves between the locking member and said leaf, with the outer ends of the sleeves projecting outwardly, means to press said locking member down toward the leaf to pinch the portions of the sleeves folded about said first mentioned pair of parallel bars in their inwardly moved positions, and means to move the first pair of parallel bars outwardly away from each other 15 back to normal position, leaving the portions of the sleeves between the locking bar and the leaf pinched against the leaf by the locking bar, a pair of spaced side flaps on the table at opposite sides of the leaf when said leaf lies on the table, and 20 said side flaps extending beyond said leaf, means to mount said flaps for swinging movement about their inner sides through an angle of 180°, said second mentioned pair of parallel bars being swingable about parallel axes spaced inwardly of 25 said second mentioned parallel bars and adjacent the side edges of the leaf, and the outer ends of said second mentioned pair of parallel bars overlying said side flaps, and means for swinging one of said flaps about its inner side to a position 30 overlying the central portion of the shirt for folding one side of the shirt over the central part of the shirt and for swinging the parallel bar of the second mentioned pair of parallel bars, overlapping said flap, about its pivotal axis through an 35 angle of 180° whereby to fold the portion of the sleeve folded about said bar over the central portion of the shirt, means to thereafter automatically swing said flap back to normal position, means to thereafter swing the other flap automatically through an angle of 180° to a position 40 overlying the central part of the shirt, for folding the other side of the shirt over the central part of the shirt and to swing the other parallel bar of said second mentioned pair of parallel bars 45 about its axis through an angle of 180° to bring the portion of the shirt folded about said other parallel bar over the central portion of the shirt, and means to thereafter automatically swing said other flap back to normal position.

4. A shirt folding machine comprising a table on which a shirt to be folded may be placed, with the front of the shirt down, means on the table to grip the collar of the shirt on the table, a leaf pivoted to the table and adapted to move from upright position down to the top of the table to overlie the central portion of the back of the shirt, a pair of parallel bars at the top of the table in spaced parallel relationship to the side edges of the leaf, and the sleeves of the shirt extending 50 outwardly and over said bars and hanging down from the sides of the table, a second pair of parallel bars overlying said sleeves and spaced inwardly from the first pair of parallel bars, a locking member pivoted to the table and movable 55 from upright position down to a position overlying the leaf when the latter is lying on the table, means to move the first pair of parallel bars inwardly toward each other to a position beneath the locking member for folding the sleeves around the second mentioned parallel bars and to bring 60 portions of the sleeves between the locking member and said leaf, with the outer ends of the sleeves projecting outwardly, means to press said locking member down toward the leaf to pinch the portions of the sleeves folded about said first 65 mentioned pair of parallel bars in their inwardly moved positions, and means to move the first pair of parallel bars outwardly away from each other 70 back to normal position, leaving the portions of the sleeves between the locking bar and the leaf pinched against the leaf by the locking bar, a pair of spaced side flaps on the table at opposite sides of the leaf when said leaf lies on the table, and 75 said side flaps extending beyond said leaf, means to mount said flaps for swinging movement about their inner sides through an angle of 180°, said second mentioned pair of parallel bars being swingable about parallel axes spaced inwardly of said second mentioned parallel bars and adjacent the side edges of the leaf, and the outer ends of said second mentioned pair of parallel bars overlying said side flaps, and means for swinging one of said flaps about its inner side to a position overlying the central portion of the shirt for folding one side of the shirt over the central part of the shirt and for swinging the parallel bar of the second mentioned pair of parallel bars, overlapping said flap, about its pivotal axis through an angle of 180° whereby to fold the portion of the sleeve folded about said bar over the central portion of the shirt, means to thereafter automatically swing said flap back to normal position, means to thereafter swing the other flap automatically through an angle of 180° to a position overlying the central part of the shirt, for folding the other side of the shirt over the central part of the shirt and to swing the other parallel bar of said second mentioned pair of parallel bars about its axis through an angle of 180° to bring the portion of the shirt folded about said other parallel bar over the central portion of the shirt, and means to thereafter automatically swing said other flap back to normal position.

mentioned pair of parallel bars in their inwardly moved positions, and means to move the first pair of parallel bars outwardly away from each other back to normal position, leaving the portions of the sleeves between the locking bar and the leaf pinched against the leaf by the locking bar, a pair of spaced side flaps on the table at opposite sides of the leaf when said leaf lies on the table, and said flaps extending beyond said leaf, means to mount said flaps for swinging movement about their inner sides through an angle of 180°, said second mentioned pair of parallel bars being swingable about parallel axes spaced inwardly of said second mentioned parallel bars and adjacent the side edges of the leaf, and the outer ends of said second mentioned pair of parallel bars overlying said side flaps, and means for swinging one of said flaps about its inner side to a position overlying the central portion of the shirt for folding one side of the shirt over the central part of the shirt and for swinging the parallel bar of the second mentioned pair of parallel bars, overlapping said flap, about its pivotal axis through an angle of 180° whereby to fold the portion of the sleeve folded about said bar over the central portion of the shirt, means to thereafter automatically swing said flap back to normal position, means to thereafter swing the other flap automatically through an angle of 180° to a position overlying the central part of the shirt, for folding the other side of the shirt over the central part of the shirt and to swing the other parallel bar of said second mentioned pair of parallel bars about its axis through an angle of 180° to bring the portion of the shirt folded about said other parallel bar over the central portion of the shirt, and means to thereafter automatically swing said other flap back to normal position, an end flap between said side flap swingable about the end thereof adjacent to the leaf through an angle of 180° to fold the central portion of the shirt over on itself, and means to thereafter automatically swing said central flap from normal position through an angle of 180°, and to thereafter automatically swing said central flap back to normal position.

5. A shirt folding machine comprising a table on which a shirt to be folded may be placed, with the front of the shirt down, means on the table to grip the collar of the shirt on the table, a leaf pivoted to the table and adapted to move from upright position down to the top of the table to overlie the central portion of the back of the shirt, a pair of parallel bars at the top of the table in spaced parallel relationship to the side edges of the leaf, and the sleeves of the shirt extending outwardly and over said bars and hanging down from the sides of the table, a second pair of parallel bars overlying said sleeves and spaced inwardly from the first pair of parallel bars, a locking member pivoted to the table and movable from upright position down to a position overlying the leaf when the latter is lying on the table, means to move the first pair of parallel bars inwardly toward each other to a position beneath the locking member for folding the sleeves around the second mentioned parallel bars and to bring portions of the sleeves between the locking member and said leaf, with the outer ends of the sleeves projecting outwardly, means to press said locking member down toward the leaf to pinch the portions of the sleeves folded about said first mentioned pair of parallel bars in their inwardly moved positions, and means to move the first pair of parallel bars

outwardly away from each other back to normal position, leaving the portions of the sleeves between the locking bar and the leaf pinched against the leaf by the locking bar, a pair of spaced side flaps on the table at opposite sides of the leaf when said leaf lies on the table, and said flaps extending beyond said leaf, means to mount said flaps for swinging movement about their inner sides through an angle of 180°, said second mentioned pair of parallel bars being swingable about parallel axes spaced inwardly of said second mentioned parallel bars and adjacent the side edges of the leaf, and the outer ends of said second mentioned pair of parallel bars overlying said side flaps, and means for swinging one of said flaps about its inner side to a position overlying the central portion of the shirt for folding one side of the shirt over the central part of the shirt and for swinging the parallel bar of the second mentioned pair of parallel bars, overlapping said flap, about its pivotal axis through an angle of 180° whereby to fold the portion of the sleeve folded about said bar over the central portion of the shirt, means to thereafter automatically swing said flap back to normal position, means to thereafter swing the other flap automatically through an angle of 180° to a position overlying the central part of the shirt, for folding the other side of the shirt over the central part of the shirt and to swing the other parallel bar of said second mentioned pair of parallel bars about its axis through an angle of 180° to bring the portion of the shirt folded about said other parallel bar over the central portion of the shirt, and means to thereafter automatically swing said other flap back to normal position, an end flap between said side flap swingable about the end thereof adjacent to the leaf through an angle of 180° to fold the central portion of the shirt over on itself, and means to thereafter automatically swing said central flap from normal position through an angle of 180°, and to thereafter automatically swing said central flap back to normal position, and a middle flap between said side flaps and between said end flap and leaf and swingable about the end thereof adjacent the leaf through an angle of 180° to a position overlying said leaf, and means to thereafter automatically swing said middle flap from normal position to a position overlying the leaf and then back to normal position.

6. A shirt folding machine comprising a table on which a shirt to be folded may be placed with the front of the shirt down, and with the sleeves of the shirt extending outwardly so as to hang down from the sides of the table, said table being formed with an opening to receive a collar of the shirt, means on the table receivable within the shirt collar for gripping said collar, means on the table for folding the sleeves about portions thereof outwardly of the shoulders of the shirt, inwardly toward the central portion of the back of the shirt and with the outer ends of said sleeves folded back over said inwardly folded portions, means on the table to grip the inner folded ends of said outwardly extending ends of said sleeves, means on the table for thereafter folding one side of the shirt and the folded sleeve on said side over the central portion of the back of the shirt, means on the table for thereafter folding the opposite side of the shirt and the folded sleeve at said side of the shirt, over the first folded side of the shirt, means on the table for thereafter folding the tail end of the central portion of the shirt over the adjacent portion of the

shirt, and means on the table for thereafter folding the folded tail of the shirt and the portion of the shirt on which it is folded over the upper central portion of the shirt.

7. A shirt folding machine comprising a table on which a shirt to be folded may be placed with the front of the shirt down, and with the sleeves of the shirt extending outwardly so as to hang down from the sides of the table, said table being formed with an opening to receive a collar of the shirt, means on the table receivable within the shirt collar for gripping said collar, means on the table for folding the sleeves about portions thereof outwardly of the shoulders of the shirt, inwardly toward the central portion of the back of the shirt and with the outer ends of said sleeves folded back over said inwardly folded portions, means on the table to grip the inner folded ends of said outwardly extending ends of said sleeves, means on the table for thereafter folding one side of the shirt and the folded sleeve on said side over the central portion of the back of the shirt, means on the table for thereafter folding the opposite side of the shirt and the folded sleeve at said side of the shirt, over the first folded side of the shirt, means on the table for thereafter folding the tail end of the central portion of the shirt over the adjacent portion of the shirt, and means on the table for thereafter folding the folded tail of the shirt and the portion of the shirt on which it is folded over the upper central portion of the shirt, said shirt collar gripping means comprising a block fixed to the table, a second block movable relative to the first block, spring means urging the second block away from the first block, a lever pivoted to the table and having an arm engaging the second block, and a second arm projecting from a side of the table against which the operator may press for swinging said lever and moving said second block toward the first block and tensioning said spring means so that the shirt collar may be placed over both said blocks and whereby when the operator moves away from the second arm of the lever, said spring means will move said second block away from the first block and grip said collar.

8. A shirt folding machine comprising a table on which a shirt to be folded may be placed with the sleeves of the shirt extending outwardly and hanging down at the sides of the table, a leaf mounted on the table and adapted to move from upright position down to a position overlying the central portion of the upper end of the shirt, means on the table to fold the sleeves of the shirt about parallel folds outwardly of the shoulders of the shirt inwardly, to overlie said leaf and to fold said inwardly folded portions outwardly about parallel folds close to one another and with the outer ends of the sleeves projecting away from each other, means on the table to automatically grip the last mentioned pair of parallel folds and press the same against said leaf, means on the table to thereafter automatically fold one side of the shirt and the folded sleeve adjacent thereto over the leaf and the central portion of the shirt, means on the table to thereafter automatically fold the opposite side of the shirt and the folded sleeve adjacent thereto over the first folded side of the shirt and its sleeve, and means on the table to thereafter automatically fold an end of the shirt over on itself.

9. A shirt folding machine comprising a table on which a shirt to be folded may be placed with the sleeves of the shirt extending outwardly and

hanging down at the sides of the table, a leaf mounted on the table and adapted to move from upright position down to a position overlying the central portion of the upper end of the shirt, means on the table to fold the sleeves of the shirt about parallel folds outwardly of the shoulders of the shirt inwardly, to overlie said leaf and to fold said inwardly folded portions outwardly about parallel folds close to one another and with the outer ends of the sleeves projecting away from each other, means on the table to automatically grip the last mentioned pair of parallel folds and press the same against said leaf, means on the table to thereafter automatically fold one side of the shirt and the folded sleeve adjacent thereto over the leaf and the central portion of the shirt, means on the table to thereafter automatically fold the opposite side of the shirt and the folded sleeve adjacent thereto over the first folded side of the shirt and its sleeve, means on the table to thereafter automatically fold an end of the shirt over on itself, and means on the table to thereafter automatically fold the folded central portion of the shirt and the portion of the shirt on which it is folded over onto the leaf.

10. A shirt folding machine comprising a table, a leaf hinged to the rear end of the table and adapted to drop from upright position to a position overlying the table, a pair of parallel sleeves at opposite sides of said leaf pivoted to the table about a horizontal axis perpendicular to the sleeves, a pair of symmetrical frames each comprising portions journaled within said sleeves, portions extending from the forward ends of said journaled portions at right angles to said portions, portions extending from the outer ends of said right angle portions forwardly and parallel to one another, and tail portions extending from the rear ends of said journaled portions, a shaft on which the sleeves are pivoted, and a handle on said shaft for turning said shaft and rotating said sleeves, and means on the table for swinging said frames outwardly away from each other upon turning the shaft to move said sleeves from upright position down to horizontal position.

11. A shirt folding machine comprising a table, a leaf hinged to the rear end of the table and adapted to drop from upright position to a position overlying the table, a pair of parallel sleeves at opposite sides of said leaf pivoted to the table about a horizontal axis perpendicular to the sleeves, a pair of symmetrical frames each comprising portions journaled within said sleeves, portions extending from the forward ends of said journaled portions at right angles to said portions, portions extending from the outer ends of said right angle portions forwardly and parallel to one another, and tail portions extending from the rear ends of said journaled portions, a shaft on which the sleeves are pivoted, and a handle on said shaft for turning said shaft and rotating said sleeves, and means on the table for swinging said frames outwardly away from each other upon turning the shaft to move said sleeves from upright position down to horizontal position, said leaf being swingable independently of said leaves, means for tilting the leaf from upright position to permit it to drop by gravity down onto the table, and means to lock the shaft on which the sleeves are mounted against rotation when the leaf is in upright position, and to release said shaft upon actuating said tilting means.

12. A shirt folding machine comprising a table, a leaf hinged to the rear end of the table and adapted to drop from upright position to a position overlying the table, a pair of parallel sleeves at opposite sides of said leaf pivoted to the table about a horizontal axis perpendicular to the sleeves, a pair of symmetrical frames each comprising portions journaled within said sleeves, portions extending from the forward ends of said journaled portions at right angles to said portions, portions extending from the outer ends of said right angle portions forwardly and parallel to one another, and tail portions extending from the rear ends of said journaled portions, a shaft on which the sleeves are pivoted, and a handle on said shaft for turning said shaft and rotating said sleeves, and means on the table for swinging said frames outwardly away from each other upon turning the shaft to move said sleeves from upright position down to horizontal position, a pair of symmetrical levers at the rear end of the table pivoted about horizontal parallel axes extending longitudinally of the table, said levers being disposed in vertical planes, and each having an upwardly and outwardly extending arm and an upwardly and inwardly extending arm, bars fixed to the upper ends of said upwardly and outwardly extending arms, said bars being normally disposed parallel to the table top and adjacent the sides thereof, and outwardly of the forwardly projecting portions of said frames, means to symmetrically oscillate said levers to bring said bars toward each other to a position overlying the leaf, and then outwardly back to normal position.

13. A shirt folding machine comprising a table, a leaf hinged to the table, a pair of parallel bars normally at the sides of the table and substantially at the plane of the top of the table, means to move said parallel bars inwardly toward each other and then outwardly back to normal position, an air motor for moving said parallel bars, a pair of side flaps spaced from one another and normally in the plane of the top of the table, and swingable inwardly about their inner sides to a position overlying a portion of the table between said side flaps and back to normal position, an air motor for actuating the swinging movement for each side flap, an end flap between said side flaps and swingable about the end thereof adjacent the leaf to overlie a portion of the table between said end flap and leaf and back to normal position, an air motor to actuate the end flap, a middle flap normally in the plane of the top of the table and swingable about the end thereof adjacent the leaf to a position overlying the leaf and back to normal position, an air motor for actuating the swinging means for the middle flap, said air motors each being controlled by a pair of solenoids, and electrical means for automatically and sequentially energizing the solenoids of said air motors.

14. A shirt folding machine comprising a table, a leaf hinged to the table, a pair of parallel bars normally at the sides of the table and substantially at the plane of the top of the table, means to move said parallel bars inwardly toward each other and then outwardly back to normal position, an air motor for moving said parallel bars, a pair of side flaps spaced from one another and normally in the plane of the top of the table, and swingable inwardly about their inner sides to a position overlying a portion of the table between said side flaps and back to normal position, an air motor for actuating the swinging

70 movement for each side flap, an end flap between said side flaps and swingable about the end thereof adjacent the leaf to overlie a portion of the table between said end flap and leaf and back to normal position, an air motor to actuate the end flap, a middle flap normally in the plane of the top of the table and swingable about the end thereof adjacent the leaf to a position overlying the leaf and back to normal position, an air motor for actuating the swinging means for the middle flap, said air motors each being controlled by a pair of solenoids, and electrical means for automatically and sequentially energizing the solenoids of said air motors, and a horizontal shaft at the rear end of the table and at the plane of the top of the table, a pair of parallel sleeves mounted on said shaft for rotation therewith, said sleeves being at right angles to said shaft, a pair of similar, symmetrically disposed shirt sleeve folding frames having portions journaled within said sleeves, and parallel portions extending forwardly and spaced from and disposed parallel to said sleeves.

15. A shirt folding machine comprising a table, a leaf hinged to the table, a pair of parallel bars normally at the sides of the table and substantially at the plane of the top of the table, means to move said parallel bars inwardly toward each other and then outwardly back to normal position, an air motor for moving said parallel bars, a pair of side flaps spaced from one another and normally in the plane of the top of the table, and swingable inwardly about their inner sides to a position overlying a portion of the table between said side flaps and back to normal position, an air motor for actuating the swinging movement for each side flap, an end flap between said side flaps and swingable about the end thereof adjacent the leaf to overlie a portion of the table between said end flap and leaf and back to normal position, an air motor to actuate the end flap, a middle flap normally in the plane of the top of the table and swingable about the end thereof adjacent the leaf to a position overlying the leaf and back to normal position, an air motor for actuating the swinging means for the middle flap, said air motors each being controlled by a pair of solenoids, and electrical means for automatically and sequentially energizing the solenoids of said air motors, and a horizontal shaft at the rear end of the table and at the plane of the top of the table, a pair of parallel sleeves mounted on said shaft for rotation therewith, said sleeves being at right angles to said shaft, a pair of similar, symmetrically disposed shirt sleeve folding frames having portions journaled within said sleeves, and parallel portions extending forwardly and spaced from and disposed parallel to said sleeves, said frames being swingable about said sleeves from a position where the forwardly projecting portions of said frames are adjacent the sides of the table to a position where the forwardly projecting portions of said frames are adjacent the side edges of said leaf, and means on the table to swing said frames outwardly upon rotating the shaft to cause said sleeves to move from upright to horizontal position.

16. A shirt folding machine comprising a table, a leaf hinged to the table, a pair of parallel bars normally at the sides of the table and substantially at the plane of the top of the table, means to move said parallel bars inwardly toward each other and then outwardly back to normal posi-

tion, an air motor for moving said parallel bars, a pair of side flaps spaced from one another and normally in the plane of the top of the table, and swingable inwardly about their inner sides to a position overlying a portion of the table between said side flaps and back to normal position, an air motor for actuating the swinging movement for each side flap, an end flap between said side flaps and swingable about the end thereof adjacent the leaf to overlie a portion of the table between said end flap and leaf and back to normal position, an air motor to actuate the end flap, a middle flap normally in the plane of the top of the table and swingable about the end thereof adjacent the leaf to a position overlying the leaf and back to normal position, an air motor for actuating the swinging means for the middle flap, said air motors each being controlled by a pair of solenoids, and electrical means for automatically and sequentially energizing the solenoids of said air motors, and a horizontal shaft at the rear end of the table and at the plane of the top of the table, a pair of parallel sleeves mounted on said shaft for rotation therewith, said sleeves being at right angles to said shaft, a pair of similar, symmetrically disposed shirt sleeve folding frames having portions journaled within said sleeves, and parallel portions extending forwardly and spaced from and disposed parallel to said sleeves, and means actuated by one of said frames for controlling the said electrical means.

17. A shirt folding machine comprising a table, a leaf hinged to the table, a pair of parallel bars normally at the sides of the table and substantially at the plane of the top of the table, means to move said parallel bars inwardly toward each other and then outwardly back to normal position, an air motor for moving said parallel bars, a pair of side flaps spaced from one another and normally in the plane of the top of the table, and swingable inwardly about their inner sides to a position overlying a portion of the table between said side flaps and back to normal position, an air motor for actuating the swinging movement for each side flap, an end flap between said side flaps and swingable about the end thereof adjacent the leaf to overlie a portion of the table between said end flap and leaf and back to normal position, an air motor to actuate the end flap, a middle flap normally in the plane of the top of the table and swingable about the end thereof adjacent the leaf to a position overlying the leaf and back to normal position, an air motor for actuating the swinging means for the middle flap, said air motors each being controlled by a pair of solenoids, and electrical means for automatically and sequentially energizing the solenoids of said air motors, said electrical means including a switch associated with each of the solenoids of said air motors, an electric motor, a shaft connected for rotation to said electric motor, and cam discs on said shaft to control said switches.

18. A shirt folding machine comprising a table, a pair of shirt sleeve folding bars adjacent the sides of the table and in the plane of the top of the table, means controlled by an air motor to move said bars toward each other from normal position and back to normal position, said air motor including a retract solenoid and an advance solenoid, a side flap at the near side of the table for folding one side of a shirt on the table, means to swing said flap about its inner side away from normal position and back to normal position, 75

and including an air motor having a retract solenoid and an advance solenoid, a side flap at the far side of the table, means including an air motor, to swing said second side flap about its inner side away from normal position and back to normal position, said last mentioned air motor having a retract solenoid and an advance solenoid, an end flap normally in a plane of the top of the table, and means including an air motor to swing said end flap about its inner end from normal position and back to normal position, said last mentioned air motor having a retract solenoid and an advance solenoid, and a central flap between said side flaps and in alignment with said end flap, and means including an air motor to swing said central flap away from normal position and back to normal position, said last mentioned air motor comprising a retract solenoid and advance solenoids, and means to automatically energize the solenoids of said air motors in predetermined sequence.

19. A shirt folding machine comprising a table, a pair of shirt sleeve folding bars adjacent the sides of the table and in the plane of the top of the table, means controlled by an air motor to move said bars toward each other from normal position and back to normal position, said air motor including a retract solenoid and an advance solenoid, a side flap at the near side of the table for folding one side of a shirt on the table, means to swing said flap about its inner side away from normal position and back to normal position, and including an air motor having a retract solenoid and an advance solenoid, a side flap at the far side of the table, means including an air motor, to swing said second side flap about its inner side away from normal position and back to normal position, said last mentioned air motor having a retract solenoid and an advance solenoid, an end flap normally in a plane of the top of the table, and means including an air motor to swing said end flap about its inner end from normal position and back to normal position, said last mentioned air motor having a retract solenoid and an advance solenoid, and a central flap between said side flaps and in alignment with said end flap, and means including an air motor to swing said central flap away from normal position and back to normal position, said last mentioned air motor comprising a retract solenoid and advance solenoids, and means to automatically energize the solenoids of said air motors in predetermined sequence, said automatic means including a switch associated with each solenoid and means to open and close said switches in predetermined sequence including a cam shaft, cam discs on said shaft, each having means to control the opening and closing of its switch, and an electric motor for rotating said shaft.

20. A shirt folding machine comprising a table, a pair of shirt sleeve folding bars adjacent the sides of the table and in the plane of the top of the table, means controlled by an air motor to move said bars toward each other from normal position and back to normal position, said air motor including a retract solenoid and an advance solenoid, a side flap at the near side of the table for folding one side of a shirt on the table, means to swing said flap about its inner side away from normal position and back to normal position, and including an air motor having a retract solenoid and an advance solenoid, a side flap at the far side of the table, means including an air motor, to swing said second side

flap about its inner side away from normal position and back to normal position, said last mentioned air motor having a retract solenoid and an advance solenoid, an end flap normally in a plane of the top of the table, and means including an air motor to swing said end flap about its inner end from normal position and back to normal position, said last mentioned air motor having a retract solenoid and an advance solenoid, and a central flap between said side flaps and in alignment with said end flap, and means including an air motor to swing said central flap away from normal position and back to normal position, said last mentioned air motor comprising a retract solenoid and advance solenoids, and means to automatically energize the solenoids of said air motors in predetermined sequence, said automatic means including a switch associated with each solenoid and means to open and close said switches in predetermined sequence including a cam shaft, cam discs on said shaft, each having means to control the opening and closing of its switch, and an electric motor for rotating said shaft, the switch controlling one of the solenoids of one of said air motors being normally closed, and the remaining switches being normally open.

21. A shirt folding machine comprising a table, a pair of shirt sleeve folding bars adjacent the sides of the table and in the plane of the top of the table, means controlled by an air motor to move said bars toward each other from normal position and back to normal position, said air motor including a retract solenoid and an advance solenoid, a side flap at the near side of the table for folding one side of a shirt on the table, means to swing said flap about its inner side away from normal position and back to normal position, and including an air motor having a retract solenoid and an advance solenoid, a side flap at the far side of the table, means including an air motor to swing said second side flap about its inner side away from normal position and back to normal position, said last mentioned air motor having a retract solenoid and an advance solenoid, an end flap normally in a plane of the top of the table, and means including an air motor to swing said end flap about its inner end from normal position and back to normal position, said last mentioned air motor having a retract solenoid and an advance solenoid, and a central flap between said side flaps and in alignment with said end flap, and means including an air motor to swing said central flap away from normal position and back to normal position, said last mentioned air motor comprising a retract solenoid and advance solenoids, and means to automatically energize the solenoids of said air motors in predetermined sequence, said automatic means including a switch associated with each solenoid and means to open and close said switches in predetermined sequence including a cam shaft, cam discs on said shaft, each having means to control the opening and closing of its switch, and an electric motor for rotating said shaft, the switch controlling one of the solenoids of one of said air motors being normally closed, and the remaining switches being normally open, and means to cause said motor to turn said shaft through one revolution from initial position and then deenergize said motor.

22. In a shirt folding machine, a table, a shirt folding flap on the table, a plurality of U-shaped links each having an arm pivoted to the table and an arm pivoted to the flap and connecting

the flap with the table, a member pivoted to said flap on an axis parallel to and spaced from the pivotal connection between said links and flap, and means to move said member to cause said links to rotate relative to the table and said flap to swing relative to said links and table over the top of said table in spaced parallel relation thereto.

23. In a shirt folding machine, a shirt receiving support, a flap in the plane of said support, a plurality of similar U-shaped links each having an arm pivoted to said support and an arm pivoted to said flap, whereby said links are swingable relative to said table and said flap is pivotable relative to said links and table to a position overlying the table in spaced parallel relation thereto, a lever pivoted to said support, a link pivoted at one end to said lever and at its other end to said flap about an axis spaced from and parallel to the axis of the pivotal connection between said bent links and said flap, and means to oscillate said lever.

24. In a shirt folding machine, a shirt receiving support, a flap in the plane of said support, a plurality of similar U-shaped links each having an arm pivoted to said support and an arm pivoted to said flap, whereby said links are swingable relative to said table and said flap is pivotable relative to said links and table to a position overlying the table in spaced parallel relation thereto, a lever pivoted to said support, a link pivoted at one end to said lever and at its other end to said flap about an axis spaced from and parallel to the axis of the pivotal connection between said bent links and said flap, and means to oscillate said lever, said means comprising an air motor including a piston connected to said lever, and said motor being provided with a retract solenoid and an advance solenoid, and means to sequentially energize said solenoids.

25. A shirt folding machine comprising a table, a leaf hinged to the table, a pair of parallel bars normally at the side of the table and substantially in the plane of the top of the table, means to move said parallel bars inwardly toward each other and then outwardly back to normal position, a pair of side flaps spaced from one another and in the plane of the top of the table, and swingable inwardly about their inner sides to a position overlying a portion of the table between said side flaps and back to normal position, means for actuating the swinging movement for each side flap, an end flap between said side flaps and swingable about the end thereof adjacent the leaf to overlie a portion of the table between said end flap and leaf and back to normal position, means to actuate the end flap, a middle flap normally in the plane of the top of the table and swingable about the end thereof adjacent the leaf to a position overlying the leaf and back to normal position, and means for actuating the swinging means for the middle flap.

26. A shirt folding machine comprising a table, a leaf hinged to the table, a pair of side flaps spaced from one another and normally in the plane of the top of the table and swingable inwardly about their inner sides to a position overlying a portion of the table between said side flaps, means for swinging said side flaps selectively inwardly over the portion of the table between the side flaps and then again outwardly back to normal position, an end flap between said side flaps and swingable about one end thereof to overlie a portion of the table between said side flaps, means for swinging said end flap to such

31

position and back to normal, and a middle flap normally in the plane of the top of the table and swingable about one end thereof to a position overlying the leaf and then back to normal position, and means for swinging said middle flap to a position overlying the leaf and then back to normal position.

27. A shirt folding device comprising a table on which a shirt may be placed with the sleeves of the shirt extending away from the body of the shirt, a form movable on to the central upper end of the shirt lying on the table and about which the shirt is to be folded, means on the table engaging beneath the outwardly extending sleeves and operable to fold portions of said sleeves inwardly of the sides of the body of the shirt with portions of the sleeves overlying said form, means on the table to fold longitudinal side parts of the body of the shirt in overlying relation with respect to one another and to overlie said form and the central portion of the shirt.

28. In combination a table on which a shirt to be folded may be placed with the sleeves of the shirt projecting outwardly and with the body of the shirt flattened on the table, a form movable on to the top of the central upper end of the shirt, means on the table engaging portions of the shirt below the sleeves, for folding longitudinal side portions of the shirt body into overlying position over the central portion of the shirt body, and means on the table to fold a portion of the tail end of the shirt over the middle part of the shirt.

29. In combination a table on which a shirt to be folded may be placed, a form movable onto

32

the top of the central upper end of the shirt, means on the table to fold one side portion of the shirt over the form and over the central portion of the shirt, means to fold the opposite side portion of the shirt over the inwardly folded side portion of the shirt, and means on the table to fold the tail ends of the folded side portions of the shirt and the central portion of the shirt over the middle central portion of the shirt.

30. In combination a table on which a shirt to be folded may be placed, a form movable onto the top of the central upper end of the shirt, means on the table to fold one side portion of the shirt over the form and over the central portion of the shirt, means to fold the opposite side portion of the shirt over the inwardly folded side portion of the shirt, and means on the table to fold the tail ends of the folded side portions of the shirt and the central portion of the shirt over the middle central portion of the shirt, and means on the table to fold the folded tail portions of the shirt and middle central portion of the shirt over the inwardly folded side portions of the shirt which overlie the form.

25 CAESAR A. CALDER.
